UNITED STATES PATENT OFFICE

WILLIAM H. DAY, OF EAST HAVEN, CONNECTICUT, ASSIGNOR, BY MESNE ASSIGNMENTS,
TO REMINGTON RAND INC., OF NEW YORK, N. Y., A CORPORATION OF DELAWARE

FILE CABINET

Application filed October 19, 1933. Serial No. 669,525.

This invention relates to index or card record equipment wherein a plurality of record carrying members, such as shallow drawers or trays, are stored away in a device 5 in the form of a cabinet and conveniently arranged for withdrawal therefrom in order to readily refer to the cards or sheets filed therein, and more particularly relates to such equipment using the type of index cards that 10 lie substantially flatwise in the drawers in overlapped relation whereby a margin of each is exposed to view.

The improved index carrying device or cabinet of my invention is primarily intended for the use of public utility corporations such as telegraph and telephone companies, and in other lines of business, where a large number of index sheets or cards are employed for directory purposes or the like, 15 and which must be readily available for immediate use. In such instances, it is desirable that the equipment be easily enlarged or added to, to care for the ever increasing volume of business. It is also desirable that a device 20 of this character be of such size and shape that it may be placed in generally unused places, such as underneath a table, counter, or like furniture, so as to leave the top surface of such furniture unobstructed, and yet 25 be located thereunder in such a manner that such device may be referred to without inconveniencing the user.

The object of this invention, therefore, is to provide such an article of index equipment, that the desirable features mentioned 30 above will be included in the construction, and which will be of simple construction, inexpensive to manufacture and of generally improved character and operation.

To these and other ends, the invention consists in the novel features and combination 35 of parts to be hereinafter described and claimed.

In the accompanying drawings:

Fig. 1 is a front elevation of a device of this character, embodying the features of this invention;

Fig. 2 is a side elevation of the same; 50 Fig. 3 is a plan view of the same, certain

portions being broken away for the sake of clearness;

Fig. 4 is a section on line 4—4 of Fig. 3;

Fig. 5 is a section on line 5—5 of Fig. 3;

Fig. 6 is an enlarged plan view of a portion of the device with a drawer partially withdrawn therefrom, certain parts being in section for the sake of clearness;

Fig. 7 is a view similar to Fig. 6, showing the arrangement of parts when the 60 drawer is to be wholly removed;

Fig. 8 is an enlarged composite end view showing the side construction of the device, portion A of which is a front view on line 8^a of Fig. 3, B is a section on line 8^b of Fig. 65 3, and C a section on line 8^c of Fig. 3;

Fig. 9 is a sectional view on line 9—9 of Fig. 3;

Fig. 10 is an enlarged plan view of an index slip holder;

Fig. 11 is a plan view of a somewhat modified arrangement of parts in a drawer;

Fig. 12 is a partial plan view of a similar device showing a somewhat modified form for certain parts and the arrangement thereof, in a similar drawer, and,

Fig. 13 is an enlarged section on line 13—13 of Fig. 12.

The device illustrated in the drawings has been selected as showing one way in which the novel features and parts may be combined to attain the objects and results contemplated. This device consists of a cabinet or frame having a plurality of shallow drawers, and both the drawers and frame are preferably 80 constructed of sheet metal, so as to combine the advantages of strength, lightness and fire resistance. The cabinet is made up of a plurality of drawer receiving sections 10, some of which, as at 11, are shown provided with

three drawer compartments 14, and others, as at 12, with two drawer compartments 14. An index card carrying member or drawer 15 is slidably mounted in each of the compartments 14, and is provided with an exterior 85 handle member 16 and an index slip holder 17. The various sections are secured together to form a complete device which is in the form of a cabinet, as illustrated in Figs.

1 and 2. This device is shown as an under- 90 95 100

hanging cabinet, being secured to the under side of a table top 13, but obviously is not limited to such a location but may be advantageously used in other ways.

5 Each of the drawer receiving sections 10, consists of a series of U shaped members 18, that extend from the front to the rear of the device or cabinet at the side portions thereof. These U shaped or channel members are 10 arranged one on top of the other, with the channel portions 19 of opposite members in opposed relation to support the drawers 15 along the sides 20 thereof and act as guiding members for the same in their sliding movements in and out of the cabinet. The two opposed series of superposed channel members 18 of each drawer-receiving section are maintained in laterally spaced relation at their front and rear ends by a strip of material 21, which is wrapped about the same and secured to each individual member, preferably by spot welding. Before being so secured, however, spacing plates 22, 23, 24 and 25 are placed between the strip of material and the channel members and are secured in place at the 20 time of welding. The spacing plates 24 and 25 at the rear of the cabinet are bent at right angles as at 26 and 27, respectively, to cover the ends of the channel members. The front spacing plate 22 is likewise bent at right angles, as at 28 and while not extending far enough to close the end of the channel member, extends over the end sufficiently to act as a drawer stop at this point. The other spacing plate 23 is terminated short at the forward end, whereby a space 29 is left between the strip 21 and the channel member 18. In this space a removable stop member 30 is located. The member 30 is bent at right angles as at 31, and like plate 22, does not close the ends of the channel member but extends over the same sufficiently to act as a drawer stop at the opposite side of the cabinet. Additional angle pieces 32 and 33 are provided and secured within each channel member at the rear end thereof. The angle pieces 32 and 33 reinforce the bent in portions 26 and 27 of the plates 24 and 25, respectively, whereby rear stops are provided for the drawers, which are 50 strong enough to withstand the constant action of the drawer without distortion. It is convenient to secure these angle pieces 32 and 33 in place at the same time the strip 21 and the plates 24 and 25 are welded to the channel members.

To avoid any longitudinal distortion of the structure so far described, bracing members 34 and 35 are provided. The bracing members 34 have a portion 36 extending outwardly at right angles to the body portion. Portion 36 is provided with suitable openings through which screws or the like may be inserted to secure the device to the underside of the table. The members 34 are located adjacent the inner edge of the strip 21 and extend

downwardly thereon a suitable distance, being secured thereto by suitable securing means, such as screws 37. One edge 38 of the members 34 is crimped over the inner edge of the strip 21 to brace the strip 21 at these 70 points and prevent lateral displacement of the structure so far described relative to the table. The bracing members 35, with the exception that portion 36 is omitted, are of the same form as members 34, but have the 75 additional features of being the connecting or coupling means between adjoining drawer receiving sections. The coupling members 35 extend from one section to another and overlap each section sufficiently to allow the 80 opposing ends of each member to abut each other. Securing means, such as screws 39 are passed through the ends of the coupling members 35 and into each section. The abutting ends of these members together with the crimped over portion 40 firmly brace the composite structure against lateral distortion. With the use of members 35, any number of 85 drawer receiving sections may be secured together and a compact and sturdy structure 90 in the form of a cabinet will be obtained, and the unlimited expansion of the directory or the like will be allowed.

The index carrying members or drawers 15, which are supported by and are slidably mounted within channel members 18, are proportioned in width to pass between the opposite inner edges of the bent over portions 28 and 31 of the respective spacing plates or front stops 22 and 30. Catches 41 and 42 are secured to the rear surface of the body of the drawer, preferably by spot welding, and extend outwardly through and beyond the sides 43 and 44 of the drawer and into the channel portions 19 of the channel members 18. The catches 41 and 42 extend beyond each side of the drawer and into the channel 19 sufficiently to act as guiding members to prevent lateral movement of the rear portion of the drawer when the drawer is withdrawn from or returned to the cabinet. The catches also act in co-operation with the bent in portions 28 and 31, respectively, to limit the drawer 15 in its outward movement, as shown in Fig. 6. The drawer portion 45 which extends rearwardly beyond the catches, co-operates with the upper wall of the channel member to support the drawer in a substantially horizontal position when so withdrawn. By removing the securing means 46, which holds the removable stop member 30 in place, this member may be removed as shown in Fig. 7, after which the drawer 15 may be swung laterally as shown in dotted lines in this figure, which removes the catch 41 from its guiding channel. The drawer may then be shifted laterally to disengage the catch 42 from the stop 28 and wholly removed from the compartment 14.

The drawer 15 comprises a body portion 47,

consisting of a single piece of sheet material bent upwardly at each side substantially at right angles, as at 48, then inwardly substantially horizontally, as at 49, back upon itself as at 50, and downwardly along the portion 48 as at 51, whereby longitudinally extending side flanges are formed. A strip of material 52 is enclosed between the bends 48, 49, 50 and 51 and extends the entire length of the sides to assist the side flanges in stiffening the drawer longitudinally. The drawer body 47 is inclined upwardly as at 53 along the rear edge to stiffen the drawer horizontally. A separate piece of material is provided and secured to the front edge of the drawer for stiffening the same. This strip of material is bent in proper shape to form a front wall 54 and a base portion 55, having its upper edge bent backwardly as at 57. The ends of the front wall 54 and bent over edge 57 are secured to the ends of the flanges at the side of the drawer, preferably by brazing or welding at 58 and 59. Mounted upon the exterior of the front wall 54 is the index slip holder 17 and the handle member 16. The handle members 16 are shown arranged in staggered relation for convenience in grasping the same especially when shallow drawers are provided.

Within the drawer and spaced from each other proportionally to the length of the index cards to be used, are card retaining strips 60 capable of removably and slidably holding index cards of the type shown at 61. The strip 60 preferably extends crosswise of the drawer as shown in Figs. 3 and 12, when the device is to be supported beneath a table, but may extend lengthwise of the drawer as shown in Fig. 11. Card edge retaining flange members 62 are also provided, having opposed flanges 64 under which the side edges of the cards are slipped to prevent them from crawling upwardly and catching on the drawer above.

The card retaining flange member 62 may be in the form shown in Figs. 3, 5 and 9 or in the form shown at 63 in Figs. 12 and 13. When the device is used as an underhanging cabinet, the latter form is preferable. In the form shown in Figs. 3, 5 and 9, the flange member 62 consists of a piece of material bent over itself along one edge forming a flange 64. The remaining portion 65, extends beyond the ends of the flanged portion and under the side flanges of the drawer 15. The member 62 is secured to the drawer body portion 47, preferably by spot welding various points along the length of the portion 65. Portion 64 of each flange member is suitably rounded at its ends, as at 66, to facilitate the insertion of cards beneath the flanges.

The members 63 shown in Figs. 12 and 13 consists of a strip of material having a base portion 67 connected by a vertical portion 68 of a flanged portion 69. The edge of the

flanged portion 69 is bent backwardly upon itself as at 70. The base 67 of these members is secured to the body portion of the drawer in the same manner as the portion 65 of the flanged member 62. The members 63 do not have opposed flanges for the cards, but in this instance, one edge of the card is located beneath the flange portion 69 of one member and abuts the vertical portion 68 of the other. Over all of the cards so mounted is a card protecting sheet of celluloid or like transparent material 71, held in place by having one of its edges inserted beneath the flanged portion 69 and having the other edge inserted between the upper surface of the flanged portion 69 and the bent over edge 70 of an adjacent member 63.

This particular card filing means is more specifically described and claimed in a co-pending application, Serial No. 749,196 filed November 11, 1924, which in some aspects is a continuation in part of this application.

The index slip holder 17 is formed from a strip of material by bulging outwardly the central portion between the ends 72 and 73 thereof to form a bottom wall 74 and an inclined front wall 75. The holder 17 is preferably secured to the front face 54 of the drawer by brazing or welding the ends 72 and 73 thereto. The bottom wall 74 abuts the bottom front edge of the drawer front 54 and is secured thereto usually by brazing. The inclined front wall 75 extends upwardly from the front edge of the bottom wall 74 toward the upper edge of the drawer front 54, leaving an opening or slit 76 formed between the same with portions 77 and 78 on each side of the opening abutting and secured to the upper edge of the drawer front 54. An opening 79 is provided in the face of the holder front wall 75 through which the interior of the same may be observed.

A card or slip 80 bearing the desired insignia is located between the front wall 75 of the holder 17 and the drawer front wall 54. This slip is formed by folding a sheet of flexible material rearwardly as at 81. The folded slip is then inserted through the opening or slit 76 and pressed downwardly into the holder 17 where the rearwardly folded portion 81, due to the tendency of the material at the bend to straighten out, presses against the wall 54 of the drawer and forces the insignia bearing portion 82 of the slip 80 against the holder wall 75, so that the insignia thereon will show through the opening 79. When the slip 80 is so located the same may be observed from above the drawer by looking in a direction parallel to the vertical front wall 54 of the drawer, which is especially convenient when the drawer is used in an underhanging cabinet.

When the above described device is used as an underhanging cabinet it is usually placed beneath the table or desk top to the

right of the user, in which position the arrangement of the card retaining strip 60 crosswise, as shown in Figs. 3 and 12, facilitates reference to the cards 61 inasmuch as a user simply glances downwardly upon the withdrawn drawer without the necessity of substantially twisting his body. This is likewise true when observing the insignia upon the index slips 80 held in the slip holders 17, due to the novel construction of the same.

From the above description, it is to be noted that the results contemplated and the objects desired have been obtained and a device has been provided which is economical to manufacture and is a decided improvement in devices of this character. While the drawings and description have been confined to a device in which a particular type of index card is used, I do not limit myself to this type of card nor to its specific retaining strip, as other types of index cards and securing means therefor may be secured within the drawer of this device with equally advantageous results. It is to be understood, therefore, that the invention is not limited to all of the details shown, but is capable of many modifications and variations which lie within the spirit of the invention and the scope of the appended claims.

What I claim is:

1. In an index or file, drawer supporting members having a drawer slidingly mounted thereon, means at the forward end of each of said supporting members co-operating to

guide the drawer in its in and out movement, said means co-operating with a portion of said drawer to prevent accidental removal of said drawer from said supports, certain of said means being removable to allow the complete removal of said drawer.

2. In an index or file, a plurality of separable sections, each section having a plurality of shallow drawer compartments comprising a plurality of channel members, said members being arranged in two series, each series having two or more members superimposed one upon the other, means to secure the superimposed members together and to connect one of said series to the other, means to secure one section to another in superimposed relation, and means to secure the uppermost section to the underside of a table top or the like, including means to brace said uppermost section against lateral movement relative to said table top.

3. In an index or file, a plurality of independent channel members mounted in superposed relation in opposed series, and a plurality of strip members encircling said series of channel members in spaced relation and rigidly securing said channel members in spaced relation and in drawer receiving unit form.

4. In an index or file, a plurality of independent channel members mounted in super-

posed relation in opposed series, a plurality of strip members encircling said series of channel members and holding the opposed series spaced from each other and rigidly securing said channel members in drawer receiving unit form, and means secured to said channel members by said strip members for limiting the sliding movement of drawers in said channel members.

5. In an index or file, a plurality of independent drawer receiving units each comprising opposed series of superposed drawer guiding members, means for securing opposed series of said guiding members in laterally spaced drawer receiving relation, and a pair of coupling members each detachably connected at a single point to each side of each unit with the inner ends of the members of each pair in abutting relation and with the outer ends thereof extending beyond the upper and lower surfaces of said unit and secured to the next adjacent units in a similar manner, the abutting ends of said members preventing pivotal movement of said members about their points of attachment to said units.

6. In an index or file, a plurality of independent drawer receiving units each comprising opposed series of superposed drawer guiding members, means for securing opposed series of said guiding means in laterally spaced drawer receiving relation, a pair of coupling members arranged on opposite sides of said unit and each detachably connected thereto at a single point and with the outer ends thereof extending beyond the upper and lower surfaces of said unit and attached to the next adjacent units, and a shoulder on said unit adapted to be engaged by said coupling members to prevent pivotal movement of said members about their points of attachment with said units.

7. In an index or file, a plurality of independent drawer receiving units each comprising opposed series of superposed drawer guiding members, means for securing opposed series of said guiding means in laterally spaced drawer receiving relation, a pair of coupling members arranged on opposite sides of said unit and each detachably connected thereto at a single point and with the outer ends thereof extending beyond the upper and lower surfaces of said unit and attached to the next adjacent units, and shoulders on said drawer guiding and coupling members adapted to abut one another to prevent pivotal movement of said members about their points of attachment with said units.

8. In an index or file, a plurality of independent drawer receiving units each comprising opposed series of superposed drawer guiding members, a strap surrounding the opposed series of superposed drawer guiding members of each series adjacent to the for-

ward and rear ends thereof and permanently secured thereto to maintain said opposed series of guiding members in laterally spaced drawer receiving relation, and a pair of coupling members mounted on each of said straps and each detachably connected thereto at a single point of attachment with the outer ends of the members of each pair extending beyond the upper and lower surfaces of said unit and secured to the next adjacent units, each of said coupling members having a flange for engagement with the edge of the adjacent strap to prevent pivotal movement of said members about their points of attachment with said units.

15 In witness whereof, I have hereunto set my hand this 12 day of October, 1923.

WILLIAM H. DAY.
